CLAIM

The ornamental design for a mosaic solar cell, as shown and described.

DESCRIPTION

FIG. 1 is a bottom perspective view of a mosaic solar cell showing my new design.

FIG. 2 is a bottom plan view of the mosaic solar cell of FIG. 1;

FIG. 3 is a top plan view thereof;

FIG. 4 is a front elevation view thereof;

FIG. 5 is a rear elevation view thereof;

FIG. 6 is a left elevation view thereof; and,

FIG. 7 is a right side elevation view thereof.
